HYDRAULIC CONTROL VALVE

Hugh J. Stacey, Willoughby, and Herbert H. Schmiel, Cleveland, Ohio, assignors to Hydraulic Equipment Company, Cleveland, Ohio, a corporation of Ohio

Application July 10, 1946, Serial No. 682,718

7 Claims. (Cl. 103—11)

1

This invention relates to a hydraulic control valve which is operable as a pump. Control valves of this general type are used in the operation of hydraulic rams or hoists and the valve of the present invention is intended to provide for emergency manual pump operation when there has been failure in the normal supply of high pressure fluid.

It is, therefore, a principal object of this invention to provide means for optionally converting a hydraulic control valve having a reciprocating plunger into a hand pump.

A more specific object of the invention resides in the combination with a hydraulic control valve of auxiliary check valve means which may be adjusted to condition the hydraulic system with which it is used for manual pump operation.

An additional specific object is to provide a simple and dependable form of auxiliary check valve means which may be set in operable relation to a hydraulic system including a control valve and a hydraulic motor device for the purpose of applying pressure to the hydraulic motor device, and unset to permit relief of the pressure thus applied.

These and other features of novelty contributing to efficiency of operation, versatility in use and ease of manufacture will be more clearly understood from the following detailed description of a preferred embodiment of the invention taken in connection with the accompanying drawings, in which:

Fig. 1 is a side elevation of a hydraulic unit comprising a pump, a control valve and a reservoir tank;

Fig. 2 is a horizontal sectional view of the control valve taken on line 2—2 of Fig. 1;

Fig. 3 represents a vertical sectional view of the control valve taken on the line 3—3 of Fig. 2; and

Fig. 4 shows an enlarged vertical section of the auxiliary check valve means, taken along the line 4—4 of Fig. 2.

With reference to Fig. 1, 10 indicates a combination hydraulic unit comprising a power driven gear pump 12, a control valve 14 and a reservoir tank 16, all joined together in compact integral relation for efficient operation.

The tank 16 is provided at the top with a breather cap and filler plug 18 and at the bottom with a drain plug 20, by means of which a hydraulic fluid such as oil may be conveniently added or removed.

The illustrative control valve 14 includes an outwardly projecting valve plunger 22 which is of

the hollow type and arranged for reciprocation by a pivotally connected operating lever 24.

A combination unit of this general type, including a hollow control valve plunger enclosing relief and check valves is disclosed in W. T. Stephens Patent No. 2,362,945, granted November 14, 1944.

Referring now to Figs. 2 and 3, it will be seen that the valve plunger 22 moves in a closely fitting plunger bore 26 extending through a chambered housing 28. Spaced pairs of vertical screws 30, 30 and 32, 32 extend through respective end passages or chambers 34 and 36 for securing the control valve 14 in tight sealing relation to the adjacent face of the reservoir tank 16. These end passages 34 and 36 intersect the plunger bore 26 to provide part of the hydraulic circuit of the valve.

As will be understood, the gear pump 12 may be rotated by any suitable motor or by a power take-off connection from a tractor or other engine-driven vehicle. The high pressure delivery end of the pump 12 is connected with an entrance port 38 extending from the bottom of the valve housing 28 to a transverse passage 40 intersecting the plunger bore 26 at a point adjacent the transverse end passage 34. A low pressure return port 42 extending downwardly from one end of the passage 34 (Fig. 2) returns hydraulic fluid to the tank 16. A central transversely extending service passage 44 also intersects the bore 26 and leads to a service port 46 which is diagrammatically shown as connected to a single acting hoist 48. A screw plug 50 closes an optional service port 52 at the other end of the passage 44.

As will appear more fully, the operation of the control valve 14 as a pump requires a fluid connection between the hoist 48 and the end passage 36 that is independent of the plunger bore 26. The relatively small displacement of the reciprocating valve plunger 22 requires, as a practical matter, that check means be included in this fluid connection in order to prevent return flow from the hoist 48 after a single pumping stroke of the plunger and before the hoist 48 has been fully extended. The preferred manner of providing the fluid connection and check means as an integral part of the valve 14 will now be explained in detail.

The upwardly extending portions of the passages 36 and 44 shown in Fig. 3 are connected by a counter bored passage 54 seating a spring pressed, ball check valve member 56 which is operative under manual pumping conditions to prevent return flow from service passage 44 to end passage 36. A transverse extension 58 of

the return passage 36 is also in circuit with the checked connecting passage 54 and connects directly with a tank return port 60 (Fig. 4), having a threadedly secured pipe 62 extending downwardly below the level of oil in the tank 16, as indicated in dotted lines in Fig. 1. The end passage 36 and its extension 58 will provide a pump chamber for cooperation with the valve plunger 22, acting as a piston, in the emergency manual operation of the control valve as a pump.

The hollow valve plunger 22 is centered in the neutral position of Fig. 2 by means of a spring 64 closely coiled around its reduced diameter right end and held in place by a screw cap 66 threaded into the plunger. A shoulder 68, which is formed by the counter boring of plunger bore 26, provides a socket and fixed abutment for the inner end of spring 64. An opposed abutment is provided at the other end of spring 64 by the adjacent portion of a hollow screw threaded cap 70 closing the corresponding end of the valve bore 26.

The hollow valve plunger 22 is formed also with an extended land portion 72 closely fitting the bore 26 at the left end, where it passes through an annular seal device 74. An elongated grooved or reduced portion 76 extends between the land portion 72 and another land portion 78, the right end of which is engageable with the centering spring 64. The hollow plunger 22 is further provided with a central passage 80 of reduced diameter, affording a seat 82 at its left end for a spring pressed ball 84 of a relief valve and a similar seat 86 at its other end for a spring pressed ball 88 of a check valve. A spaced series of radially extending ports 90, 90 is formed in the hollow plunger 22 adjacent the relief valve ball 84 and a similar set of radially extending ports 92, 92 is formed in the land portion 78 and between the two valve balls 84 and 88. In its seated position the check valve ball 88 is encircled by a further group of radially extending ports 94, 94 which also pass through the land portion 78 of the plunger 22.

Fig. 4 shows a fragmentary section of the chambered housing 28 which has a step bored opening 96 for accommodation of a plug type check valve 98 which is employed in the manual pumping operation. The opening 96 has a threaded lower end portion 100 engaging a corresponding threaded end 102 of a hollow cylindrical cap 104. This cylindrical cap 104 is formed with an intermediate, extended, shoulder portion 106, slidable in the enlarged upper part of the bored opening 96 and grooved intermediate its length to receive a peripheral sealing ring 108. The cap 104 also includes a head 110 which is shown to be in engagement with a slotted retaining ring 112 attached to the valve housing 28 by means of screws 114, 116. The washer-like retaining ring 112 cooperates with head 110 to prevent insertion of the hollow cap 104 beyond the position of Fig. 4, and also to prevent undesired withdrawal of this cap by serving as a stop for the shoulder portion 106.

In normal, upright position of the control valve 14 the check valve 98 will close promptly without assistance from the compression spring 118, but to insure its efficient functioning in all possible operating positions the spring should be used.

The head 110 of the hollow cap 104 is threaded to receive a screw plug 116 against which reacts the upper end of a compression spring 118 arranged to hold the check valve 98 resiliently

seated against return port 68. It will also be noted that the check valve 98 has an extended shoulder 120 snugly fitting within the cylindrical cap 104 and that an inwardly extending flange 122 on the lower end of this cap is engageable with shoulder 120 to prevent separation of the valve 98 from the cap.

In Fig. 1 the check valve assembly is shown in a raised position which results in a positive unseating of the check valve 98 by the flange 122, and its elevation to a position clear of the tank return port 60 and the adjacent return passage extension 58.

In normal operation the check valve 98 will not be used, but if for any reason other than a shortage of hydraulic fluid the pump 12 becomes inoperative, the hoist 48 can be extended by utilization of the plunger 22 as a hand pump, and can be subsequently retracted by proper manipulation of the cap 104 supporting the check valve 98 to clear the return port 60. The functions of the control valve and the auxiliary check valve will now be described in detail.

When the valve plunger 22 is in the neutral position shown by Fig. 2, pressure fluid entering the valve housing 28 from the high pressure inlet port 38 will reach chamber 40, flow freely through the valve bore 26 adjacent the plunger grooved portion 76, and thence into the end passage 36. The port 42 extending into the passage 36 will return the thus bypassed hydraulic fluid back to the tank 16.

Pulling the plunger 22 out, that is, moving it to the left of the position shown in Figs. 2 and 3 and against the action of compression spring 68, will place the intermediate plunger ports 92, 92 in communication with the passage 40 and the end ports 94, 94 in communication with the central service passage 44. Fluid under pressure will then flow from the inlet 38 to the passage 40, through the ports 92, 92 and along the central plunger passage 80 to unseat the check valve ball 88 and discharge pressure fluid into the service passage 44. This pressure fluid will continue its flow from the passage 44 to the hoist 48 for the operation of whatever device is attached thereto.

Reverse movement of the valve plunger 22 inwardly against the compression spring 68 abutting the hollow cap 70 will result in a return flow of hydraulic fluid from the hoist 48 as the plunger ports 92, 92 are placed in communication with the service passage 44, and the end ports 94, 94 are opened by the check valve ball 88 to the passage 36 which leads to the passage extension 58 and the tank return port 60.

The relief valve ball 84 will be unseated if abnormal pressure is built up during the extend operation of hoist 48, in which event the pressure will be relieved by exhaust through the plunger ports 90, 90, which are at that time open to the end passage 36 connected to the low pressure return port 42.

Assuming a power failure or breakdown of the gear pump 12 when the hoist 48 is in the position indicated in Fig. 2, it will be possible to extend it manually by turning down the head 110 to permit the spring 118 to resiliently seat the check valve 98 in the return port 60, thus preventing return flow of fluid to the tank 16. Reciprocation of the hollow valve plunger 22 will then produce a pumping action effective to extend the hoist 48. As the plunger 22 is pulled out to the left of Fig. 2 a vacuum will be created in passage 36 causing the valve 98 to be lifted from its seated position and fluid under

atmospheric pressure in the tank 16 to enter the valve housing 28 by way of port 60. When the plunger 22 is pushed in the opposite direction the check valve 98 will move to closed position and fluid under pressure will be forced through the end passage 36, to the check valve member 58, through passage 54 and into the service passage 44, whence it will flow to the hoist 48. This reciprocating operation will be repeated until the hoist 48 has been moved to its extended position or any intermediate position which is desired.

To retract the hoist 48, it is necessary that the head 110 be turned to unscrew the threaded end 102 of the hollow cap 104, which will raise the check valve 98 clear of its seat and allow return flow from the chamber 36 to the reservoir 16. This return flow is then accomplished by moving the plunger 22 inwardly to its normal retracting position.

The advantages offered by the novel means which have been provided for the emergency operation of a plunger type control valve as a pump will now be fully apparent. As a practical example, it may be noted that the blade of a bulldozer left in grounded position by failure of power or gear pump may be conveniently and efficiently lifted with the pump operable valve of this invention, thus permitting towing of the vehicle on which the bulldozer blade is mounted.

As it will be obvious to those skilled in this art that the principles of the invention which have been specifically described herein may be varied in details and mode of application, it is not intended that the invention shall be limited other than as may be required by the scope of the appended claims.

Having thus described our invention, what we claim as novel and desire to secure by Letters Patent of the United States is:

1. In a hydraulic control valve, the combination comprising a valve housing provided with an inlet passage for pressure fluid, a service passage spaced at one side of the inlet passage, a return passage spaced farther from the inlet passage on the same side, a plunger bore intersecting the said passages, a valve plunger reciprocable in said bore and formed for operable cooperation with said passages, an enclosed intercommunicating passage extending between the return passage and the service passage and separate from the plunger bore, a check valve arranged to prevent flow in the intercommunicating passage from the service passage to the return passage, and an auxiliary check valve assembly mounted in said housing and optionally movable to a position in the return passage to prevent the return of hydraulic fluid therethrough.

2. In a hydraulic control valve, the combination comprising a valve housing provided with an inlet passage for pressure fluid, a service passage spaced at one side of the inlet passage, a tank return passage spaced farther from the inlet passage on the same side, and a plunger bore intersecting the said passages; a valve plunger reciprocable in said bore and formed for operable cooperation with said passages, said valve housing being also provided with an intercommunicating passage between the service passage and the tank return passage spaced laterally from the bore, a check valve arranged to prevent flow in the intercommunicating passage from the service passage to the tank return passage; and an auxiliary check valve assembly mounted in said housing and positionable to prevent nor-

mal return flow of hydraulic fluid from the tank return passage, whereupon the control valve may be operated as a pump, said auxiliary check valve assembly being also positionable to permit unrestricted flow out of the tank return passage when the control valve is not to be operated as a pump, and said auxiliary check valve assembly including a check valve member, and a sleeve threaded into said housing and supporting the check valve member, whereby the check valve member may be moved from an inoperative to an operative position with respect to said tank return passage by rotation of the sleeve from without the housing.

3. In a hydraulic control valve for use with a single acting hoist, the combination comprising a valve housing provided with a pressure fluid inlet passage, a service passage, and a tank return passage spaced in the order recited, a plunger bore intersecting the said passages, and an interconnecting passage between the service passage and the tank return passage laterally spaced from the plunger bore; a valve plunger reciprocable in said bore and formed for operable cooperation with the passages intersected thereby; one-way check means associated with the connecting passage and constructed and arranged to permit flow of hydraulic fluid from the tank return passage to the service passage; and an auxiliary check valve assembly mounted in said housing and manually positionable to prevent normal return flow of hydraulic fluid from the tank return passage, whereupon the control valve may be operated as a pump, said auxiliary check valve assembly being also optionally and manually positionable to permit unrestricted flow out of the tank return passage when the control valve is not to be operated as a pump.

4. In a hydraulic control valve for use with a single acting hoist, the combination comprising a valve housing provided with a pressure fluid inlet passage, a service passage, and a tank return passage spaced in the order recited, a plunger bore intersecting the said passages, and an interconnecting passage separate from the bore extending between the service passage and the tank return passage; a valve plunger reciprocable in said bore and formed for operable cooperation with the passages intersected thereby; one-way check valve means associated with the connecting passage and constructed and arranged to permit flow of hydraulic fluid from the tank return passage to the service passage; and an auxiliary check valve assembly mounted in said housing and positionable to prevent normal return flow of hydraulic fluid from the tank return passage, whereupon the control valve may be operated as a pump, said auxiliary check valve assembly being also positionable to permit unrestricted return flow of hydraulic fluid from the tank return passage when the control valve is not to be operated as a pump, and said auxiliary check valve assembly including a check valve member, and a sleeve threaded into said housing and supporting the check valve member, whereby the check valve member may be moved from an inoperative to an operative position with respect to said tank return passage by rotation of the sleeve from without the housing.

5. The combination with a reservoir tank constructed to expose a contained hydraulic fluid to atmospheric pressure, of a hydraulic control valve having a valve housing provided with a plunger bore, said housing having an inlet passage for high pressure fluid, a discharge passage at one

side of the inlet passage, a service passage on the other side of said inlet passage for connection to a hoist, a return passage beyond the hoist passage, and an intercommunicating passage between the return passage and the service passage spaced laterally from the bore; a conduit connected to the return passage and adapted to extend below the level of hydraulic fluid in said tank; a check valve arranged to prevent flow in the intercommunicating passage from the service passage to the return passage; a valve plunger reciprocable in said bore and ported for cooperation with said passages, said porting being such that in the neutral position of the plunger the first two passages are in full open communication, the remaining passages positively closed, and said hoist connection passage being closed against flow in either direction; and a pump check valve positionable in the return passage and arranged to prevent return of hydraulic fluid therethrough to the tank, whereby reciprocation of the plunger in one direction will produce a vacuum in the return passage and induce a flow of fluid from the tank past the pump check valve, and reciprocation in the other direction will force fluid from the return passage to the service passage.

6. The combination with a reservoir tank constructed to expose a contained hydraulic fluid to atmospheric pressure, of a hydraulic control valve having a valve housing provided with a plunger bore, said housing having an inlet passage for high pressure fluid, a discharge passage at one side of the inlet passage, a service passage on the other side of said inlet passage for connection to a hoist, a return passage beyond the hoist passage, and an intercommunicating passage between the return passage and the service passage spaced laterally from the bore; a conduit connected to the return passage and adapted to extend below the level of hydraulic fluid in said tank; a check valve arranged to prevent flow in the intercommunicating passage from the service passage to the return passage; a valve plunger reciprocable in said bore and ported for cooperation with said passages, said porting being such that in the neutral position of the plunger the first two passages are in full open communication, the remaining passages positively closed, and said hoist connection passage being closed against flow in either direction; and a pump check valve assembly positionable in the

5
10
15

25

return passage and arranged to prevent return of hydraulic fluid therethrough to the tank, whereby reciprocation of the plunger in one direction will produce a vacuum in the return passage and induce a flow of fluid from the tank past the pump check valve assembly, and reciprocation in the other direction will force fluid from the return passage to the service passage, and said pump check valve assembly including a spring-seated check valve member, and a sleeve threaded into said housing and supporting the check valve member, whereby the check valve member may be moved to a wholly inoperative position by rotation of the sleeve.

7. A combined hydraulic control valve and pump, comprising, a valve housing provided with a pressure fluid inlet passage, a service passage spaced at one side of the inlet passage, a fluid return passage spaced farther from the inlet passage on the same side and adapted to form a pump chamber, a valve plunger bore intersecting the said passages, and an enclosed intercommunicating passage extending between the return passage and the service passage and separate from the plunger bore; a valve plunger reciprocable in said bore and ported for cooperation with said inlet, service and return passages, the porting being such that in the neutral position of the plunger the inlet passage and the service passage are closed to communication and the service passage is closed to the return passage; check valve means arranged to prevent flow in the intercommunicating passage from the service passage to the return passage; and a pump check valve adjustably mounted in the valve housing and optionally movable to a pumping position in the return passage preventing normal return of hydraulic fluid therethrough.
